UNITED STATES PATENT OFFICE.

CHARLES PRESCOTT CATLIN, OF DULUTH, MINNESOTA.

DESIGN FOR A HANDLE FOR ALARM-CLOCKS.

40,972.

Specification for Design.

Patented Nov. 8, 1910.

Application filed April 21, 1910. Serial No. 556,908. Term of patent 14 years.

To all whom it may concern:

Be it known that I, CHARLES PRESCOTT CATLIN, a citizen of the United States, residing at No. 212 North Fifteenth avenue east, in the city of Duluth, in the county of St. Louis and State of Minnesota, have invented a new, original, and ornamental Design for Handles for Alarm-Clocks, of which the following is a specification, reference being had to the accompanying drawing, forming a part thereof.

The figure is a plan view of the handle of an alarm clock showing my new design.

I claim:

The ornamental design for a handle for alarm clocks as shown.

CHARLES PRESCOTT CATLIN.
